Primary Examiner — George D Kirschbaum*(74) Attorney, Agent, or Firm* — Christensen O'Connor Johnson Kindness PLLC(57) **CLAIM**

The ornamental design for a wheel hub, as shown and described.

DESCRIPTION

FIG. 1 is an isometric view of a first embodiment of a wheel hub according to our new design;

FIG. 2 is a top view of the wheel hub of FIG. 1;

FIG. 3 is a side view of the wheel hub of FIG. 1;

FIG. 4 is an auxiliary side view of the wheel hub of FIG. 1;

FIG. 5 is an isometric view of a second embodiment of a wheel hub according to our new design;

FIG. 6 is a top view of the wheel hub of FIG. 5;

FIG. 7 is a side view of the wheel hub of FIG. 5; and,

FIG. 8 is an auxiliary side view of the wheel hub of FIG. 5. The broken lines depict unclaimed environmental subject matter.
